UNITED STATES PATENT OFFICE.

LEE E. RAINBOLT, OF BEDFORD, INDIANA.

NAIL-DRIVING MACHINE.

1,192,932.

Specification of Letters Patent. Patented Aug. 1, 1916.

Application filed December 8, 1914. Serial No. 876,110.

To all whom it may concern:

Be it known that I, LEE E. RAINBOLT, a citizen of the United States, residing at Bedford, in the county of Lawrence and State of Indiana, have invented a new and useful Nail-Driving Machine, of which the following is a specification.

The present invention relates to improvements in nail driving machines, one object 10 of the invention, being the provision of a machine that will drive a nail through a plurality of thicknesses of material, preferably paper bags, so that the nail may remain therein and thus hold the bags in position 15 upon display racks as is the customary practice in grocery and other stores.

A further object of the present invention, is the provision of a nail driving machine of 20 this character, in which the bags to receive the nail are normally held in a compact or compressed position during the initial driving of the nail, the grip for holding the nail being a sectional grip, so that when the hammer for finally driving the same is operated, the sectional gripping member will be 25 opened to permit of the proper release of the nail and the final driving thereof.

A still further object of the invention, is the provision of a machine of this character 30 which is exceedingly simple in construction and operation, and therefore efficient and practical in use.

With the foregoing and other objects in view which will appear as the description 35 proceeds, the invention resides in the combination and arrangement of parts and in the details of construction hereinafter described and claimed, it being understood that changes in the precise embodiment of the 40 invention herein disclosed can be made within the scope of what is claimed without departing from the spirit of the invention.

In the drawings—Figure 1 is a side elevation of the complete implement with the 45 parts in the position they normally assume. Fig. 2 is a front elevation thereof. Fig. 3 is a view similar to Fig. 1 taken from the opposite side of the machine. Fig. 4 is an enlarged front elevation of the lower part of 50 the machine showing the driving member in its lowermost position with the nail clamp and holder in open position. Fig. 5 is a detailed sectional view taken through the nail clamp and holder. Fig. 6 is a detail view 55 showing a modified mounting for the guide.

Referring to the drawings, the numeral 1

designates the base, which has fixedly secured thereto the plate 2 which carries the upstanding paper guides 3, there being two of these guides, so that the paper, as for instance bags may be inserted thereagainst to properly receive the nail 17 which acts as a holding means when used in connection with the usual form of bag rack. Mounted adjustably upon the base 2 between the guides 60 3 is the foot 4 which is adjustably held in place by means of the set screws 5. Formed integral with the foot 4 is an upright 6, carrying a forwardly extended open frame 7 at the upper end. Mounted in the frame 7 for 65 vertical reciprocatory movement, is the stem or rod 8, which has mounted thereupon within the frame 7, the spring 9. This spring normally exerts a tension downwardly upon a pin 10 carried by the rod 8, so as to hold 70 down the member 11 carried by the rod. Thus a presser foot 12 carried by rod 8 will be pressed downwardly to resiliently hold and compress a stack of bags (not shown) 75 theretherein. The presser foot 12 is provided near its center with the nail guiding slot 13 so that the nail 17, as clearly illustrated in Fig. 4, will be guided therethrough and finally into the aligned slots 2' and 1' of the respective base members 2 and 1. These 80 slots also permit the bags, with the attached nail, to be moved forwardly from beneath the presser foot.

Connected to the front face of the member 11 above the presser foot 12 by means 85 of pivot screws 14, are the laterally swinging members 15, which are socketed as at 16 for the reception of the nail 17, there being provided the rod 18 which is loosely mounted in both of the pivoted members so that 90 the respective springs 19 carried thereby will hold the members 15 toward each other thus to properly grip the nail 17 therebetween, whereby, upon the initial movement of the member 11 downwardly, the point of 95 the nail will be projected through the slot 13 and into the bags a sufficient distance to permit the nail to stand alone during the final operation of the present device.

In order to provide a means for elevating 100 the member 8, and cause the presser foot 12 and the nail guide member 15 to assume the position as shown in Fig. 3, there is pivoted at one side of the machine at 20, the operating handle 21, said handle 21 being provided with a cam 22 which rides beneath one 105 end of the pin 10 thus to elevate rod 8 against

the action of the spring 9. Thus it will be necessary to move the lever 21 from the position shown in Fig. 3 to that shown in Fig. 1, to permit the presser foot 12 to be lowered in resilient engagement with the pack of bags after a nail has been inserted between the members 15 with the point thereof below the presser foot 12.

Mounted for vertical sliding movement 10 within the frame 7 and parallel to the stem or member 8, is the driving member 23, which is provided with the head 24, that constitutes a blow receiving member, but which may, if desired, be operably connected to a foot treadle so that the member 23 may be actuated thereby. The lower reduced end 25 of the member 23 constitutes the driving portion thereof. Thus when the member 15 with the nail therein is lowered, 20 as shown in Fig. 1, the member 25 will be co-axial with the upper end of the nail 17 so that when the same is driven from the position as shown in Fig. 2 to the position as shown in Fig. 4, the head of the nail will 25 be primarily engaged with the lower end of the member 23 and will thus be driven practically the full distance of the jaws or members 15 before the enlarged portion of the member 23 engages the jaws to separate them and thus free the said jaws from the nail.

The tensions of the springs 18 are such as to normally grip the nail between the members 15 with sufficient pressure to permit when the spring 9 is released and the presser 35 foot 12 is lowered to cause the point of a nail to be driven through a sufficient thickness of the bags to be maintained in a vertical position and started before receiving the final blow from the member 25 when the 40 rod 23 is driven, either by the hand, hammer or by foot power as may be found desirable. Or the clamp may hold the nail during the complete driving operation, the clamp being operated simultaneously with the final setting 45 of the nail.

Carried upon one side of the frame or support 6 is a nail receptacle 26.

In the construction shown in Fig. 6, the member 4' is held rigidly upon the base 1^a, 50 while the base 2^a is adjustable, this being the reverse of the structure heretofore described.

It will thus be seen that by adjusting the foot 4 in the construction shown in Fig. 1 through Fig. 4, that the position of the 55 presser foot 12 relatively to the guides 3 will be changed, so that the nail may be driven at various distances from the edge of the bag, while in the construction shown in Fig. 6, the guides are adjustable and the 60 frame remains fixed at all times.

What is claimed is:

1. A nail driving machine, including a support, a spring actuated reciprocating member having a presser foot and a resilient nail grip and guide and mounted in the sup-

port, manually controlled means for operating the same in opposition to the spring to hold the presser foot elevated, and a reciprocating driving means mounted in the support and disposed to have one end 70 cooperate with the nail grip and guide.

2. A nail driving machine including a spring pressed presser foot having a slot extending thereinto, opposed nail gripping elements supported above and movable with the presser foot, and means movably mounted above the nail gripping elements for driving a nail longitudinally between said elements and into an object held under the presser foot, said slot permitting the nail 75 to be moved laterally from the presser foot.

3. A nail driving machine including a spring pressed presser foot having a slot extending thereinto, opposed nail gripping elements supported above and movable with the presser foot, means movably mounted above the nail gripping elements for driving a nail longitudinally between said elements and into an object held under the presser foot, said slot permitting the nail 80 to be moved laterally from the presser foot, and guides adjustably mounted at the sides of the presser foot and constituting abutments for the nail receiving object under the 85 presser foot.

4. A nail driving machine, including a support, a spring actuated reciprocating member mounted therein, a presser foot carried upon the lower end thereof, a sectional nail grip and guide carried by the reciprocating member, means for resiliently holding such sections together in nail gripping and guiding relation, a reciprocating driving member mounted in the support and having its lower end disposed for movement 100 between the sections of the guide for driving the nail therein and for actuating the members to release the nail, and manually controlled means for operating the reciprocating member in opposition to its spring to 105 maintain the same in upward position.

5. A nail driving machine, including a support, a spring actuated reciprocating member mounted therein, a presser foot carried upon the lower end thereof, manually 110 controlled means for operating the reciprocating member in opposition to the spring to hold the presser foot elevated, a sectional nail gripping guide mounted upon and carried by the reciprocating member, the same being provided with a nail receptacle the lower end of which is open and disposed adjacent to the presser foot, said presser foot being provided with a slot to receive the nail 115 from the grip and guide, a rod mounted through the sections of the guide, two springs connected upon the rod for holding the sections of the guide in gripping relation, and a reciprocating driving member mounted in the support and having one end 120

125

130

- for coöperation with the nail gripping guide to drive the nail while gripped and for releasing the sections of the guide therefrom.
6. A nail driving machine, including a support, a spring actuated reciprocatory member mounted therein, a presser foot carried upon the lower end thereof, manually controlled means for operating the reciprocatory member in opposition to the spring to hold the presser foot elevated, a sectional nail gripping guide mounted upon and carried by the reciprocatory member, the same being provided with a nail receptacle, the lower end of which is open and disposed adjacent to the presser foot, said presser foot being provided with a slot to receive the nail from the grip and guide, a rod mounted through the sections of the guide, two springs connected upon the rod for holding the sections of the guide in gripping relation, a reciprocatory driving member mounted in the support and having one end for coöperation with the nail gripping guide to drive the nail while gripped and for releasing the sections of the guide therefrom, and manually controlled means for actuating the reciprocatory member in opposition to its spring.
7. A nail driving machine, including a base, a frame mounted upon the base, an article guide also mounted upon the base, a reciprocatory rod mounted in the frame, a presser foot carried upon the lower end of said rod for coaction with the guide and base to clamp the material to receive the nail thereupon, two swingingly mounted sections carried upon the lower end of the rod above the presser foot, said sections being provided with coöperating recesses to form a nail guiding and gripping means, resilient means for holding the sections together in nail gripping relation, and a reciprocatory driving member mounted in the frame and disposed to coöperate with the pivoted sections to drive the nail while gripped therein and for releasing such sections from the nail at the final operation of the driving member.
8. A nail driving machine, including a base, a frame mounted upon the base, an article guide also mounted upon the base, a reciprocatory rod mounted in the frame, a presser foot carried upon the lower end of the said rod for coaction with the guide and base to clamp the material to receive the nail thereupon, two swingingly mounted members carried upon the lower end of the rod above the presser foot, said members being provided with coöperating recesses to form a nail guiding and gripping means, resilient means for holding the sections together into nail gripping relation, a spring for operating the rod to hold the presser foot downwardly, manually controlled means for operating the rod and the presser foot against the action of the spring, and a reciprocatory driving member mounted in the frame and disposed coaxially with the recess of the pivoted members.

In testimony that I claim the foregoing as my own, I have hereto affixed my signature in the presence of two witnesses.
